ELECTRICAL CONNECTOR HOUSING OR SIMILAR ARTICLE

Clair Wilson Snyder, Jr., Hellam, Pa., assignor to
AMP Incorporated, Harrisburg, Pa.

Filed Apr. 25, 1968, Ser. No. 11,611

Term of patent 14 years

U.S. Cl. D26—1
Int. Cl. D13—03

FIGURE 1 is a perspective view of an electrical connector housing or similar article showing my new and ornamental design;

FIGURE 2 is a front elevational view of the electrical connector housing or similar article shown at an enlarged scale;

FIGURE 3 is a side elevational view of the electrical connector housing or similar article as seen in FIGURE 1;

FIGURE 4 is a top plan view of the electrical connector housing or similar article; and

FIGURE 5 is a bottom plan view of the electrical connector housing or similar article.

The figures show a part broken away to indicate indefinite length.

The dominant features of my design are in the portions shown in full lines.

I claim:

The ornamental design for an electrical connector housing or similar article, substantially as shown and described.
